GARMENT HANGER

Filed Sept. 12, 1938

UNITED STATES PATENT OFFICE

2,219,520

GARMENT HANGER

Reynolds Guyer, St. Paul, Minn., assignor to Wal-
dorf Paper Products Company, St. Paul, Minn.,
a corporation of Minnesota

Application September 12, 1938, Serial No. 229,403

3 Claims. (Cl. 223—98)

My invention relates to garment hangers and particularly to garment hangers constructed with wire frame members and has for an object to provide supporting means attached to one or 5 more of the frame members by means of which garments supported thereon are supported throughout a greater area than where directly supported on the frame members, thereby preventing creasing.

10 Another object of the invention resides in providing a garment hanger in which the supporting means may be folded into the plane of the frame of the hanger to occupy a minimum amount of space when in disuse.

15 An object of the invention resides in constructing the garment hanger with a frame formed of wire to provide converging side frame members and a cross frame member all lying in a common plane, and in providing the supporting means 20 with three supporting members, one attached to each frame member of the frame.

A feature of the invention resides in constructing said supporting members substantially planiform and in pivoting the same to the frame 25 members for pivotal movement about the axes of said frame members so that the said supporting members may be moved from positions substantially in the plane of said frame to positions extending transversely of the plane of the frame.

30 Another object of the invention resides in constructing said supporting members from strips of paper and in pivoting said supporting members longitudinally of the strips and medially of the lateral edges thereof to said frame members.

35 An object of the invention resides in constructing the supporting members from two thicknesses of paper secured together marginally and providing a space therebetween through which the frame members extend and by means of which 40 the supporting members are pivotally attached to the frame members of the frame.

With the foregoing and other objects in view, which will appear in the following description, the invention resides in the novel combination 45 and arrangement of parts and in the details of construction hereinafter illustrated and/or described.

In the drawing:

Fig. 1 is a perspective view of a garment hanger 50 illustrating an embodiment of my invention and showing the supporting members in erected position.

Fig. 2 is an elevational view of the structure shown in Fig. 1 with the supporting members in 55 collapsed position.

Fig. 3 is a cross sectional view taken on line 3—3 of Fig. 1.

Fig. 4 is a cross sectional view taken on line 4—4 of Fig. 2.

Fig. 5 is a cross sectional view of a modification 5 of the invention.

In the use of wire garment hangers considerable difficulty has been encountered due to the fact that the frame members of the hanger afford insufficient area for supporting the garments and when the garments remain on the hangers for any appreciable length of time creases are formed in the garments. It has heretofore been attempted to utilize paper supporting members which are applied to the hanger when 10 the same is to be put into use. Such devices are inconvenient to use and frequently become disengaged when the garments are applied to the hanger, thereby causing considerable inconvenience and failing to produce the desired results. 15 Paper garment hangers have been completed which overcome these disadvantages but these occupy an appreciable amount of space and where large numbers of garment hangers are employed the packages containing the same become 20 extremely bulky. The present invention provides a construction in which all of the disadvantages of the wire hanger are overcome and in which the advantages of both the wire and paper garment hangers are procured. 25

My invention as best shown in Fig. 2 consists of a frame 10 constructed from a single piece of wire, which is formed intermediate its ends with bent parts 11, 12, 13 and 14 to provide two converging side frame members 15 and 16 and a 30 cross frame member 17.

The ends 18 and 19 of the piece of wire from which the frame is constructed are twisted together, as indicated at 21, to form a shank which I have designated by the reference numeral 22. 40 The end 18 terminates at the locality of this shank, while the end 19 projects outwardly beyond the same and is bent to form a hook 23, by means of which the garment hanger may be hung upon a pole, hook, or other support. 45

Attached to the frame 10 is a supporting means indicated in its entirety by the reference numeral 24. This supporting means consists of three supporting members 25, 26, and 27, of which the supporting member 25 is attached to the frame 50 member 15, the supporting member 26 is attached to frame member 16, and the supporting member 27 is attached to the frame member 17. These various supporting members will now be described in detail. 55

The supporting member 27 consists of two strips or layers of paper 28 and 29, which are elongated in form and of sufficient width to give the desired supporting area when the garments 5 are mounted upon the same. These strips are formed with two longitudinal scores 31 and 32, which divide the strips into central portions 33 and marginal portions 34 and 35. The marginal portions 34 and 35 are secured together by gluing, 10 while the intermediate or central portions 33 are free from glue to provide longitudinally extending spaces 36 therebetween. In the attachment of the supporting member 27 to the frame member 17 the two strips 28 and 29 are first coated 15 with adhesive upon the marginal portions 34 and 35 thereof which face one another, and the said strips placed one above and one below the wire frame member 17. Pressure is then applied to the marginal portions of the strips which causes 20 the same to become attached to one another and the parts then take the form shown in Fig. 2.

In order to prevent interference between the various supporting members when applying the same to the frames, the strips are preferably at 25 right angles to the plane of the frame 10 when applied thereto and are of the form shown in Fig. 4, being substantially planiform.

The two supporting members 25 and 26 are 30 constructed in identically the same manner as the supporting member 27 and the description thereof will not be repeated. These supporting members are also preferably attached to the frame members 15 and 16 while in a position at right angles to the plane of the frame 10.

The supporting member 27 is of a length 35 greater than the length of the frame member 17 and is constructed at its ends with two notches 37 and 38. By means of this construction tabs 39 are formed on the ends of the supporting 40 member 27, which tabs are adapted to straddle the bent parts 11 and 12 of the frame 10 when the supporting member is swung into operative position, thus causing said bent parts to be received within the notches 37 and 38. The tabs 45 39 thus limit the rotation of the supporting member 27 by engagement with the bent portions 11 and 12, thereby maintaining the same in operative position.

The converging frame members 15 and 16 are 50 constructed at their upper ends with substantially horizontal portions 41 adjoining the bends 13 and 14. The supporting members 25 and 26, similar to the supporting member 27, are formed with notches 42 which provide at the ends of said 55 supporting members tabs 43. The portions 41 of the frame members 15 and 16 are adapted to be received in the notches 42 as shown in the Fig. 2 and the tabs 43 engage the horizontal portions 41 and limit turning of the supporting 60 members in the same manner as the tabs 32.

The use of the invention is as follows. When the garment hangers are constructed at the factory, they come as shown in Fig. 2 with the supporting members 25, 26 and 27 disposed substantially in the plane of the frame 10 and with the said supporting members arranged with reference to one another and to the frame as illustrated. By means of the construction shown, the supporting members become pivotally mounted upon 65 the frame members by means of the elongated spaces 36 formed between the strips 28 and 29 of the said supporting members, thus permitting the supporting members to be swung from positions in the plane of the frame 10, as shown in 70 Fig. 2, to positions at right angles thereto, as 75

shown in Fig. 1. After erection of the parts, the tabs 39 of the supporting member 27 straddle the bent portions 11 and 12 of the frame 10, and the bent portions 11 and 12 are received in the notches 37 and 38. Thereafter the supporting 5 member 27 is squeezed together and bent along the scores 31 and 32, which cause the strips 28 and 29 of the supporting member to buckle at the central portion 33 thereof and which gives to the supporting member 27 a U-shaped cross section. 10 Since the supporting members 25 and 26 are constructed in the same manner, the said supporting members may be swung outwardly and formed to give the same U-shaped cross section, 15 as shown in Fig. 3. Since the vertical portions 41 15 of the frame members 15 and 16 normally occupy the same relation with respect to the notches 42 as the bent portions 11 and 12 occupy with reference to notches 37, the supporting members 25 and 26 may be moved into erected position in the 20 same manner. After the parts have been erected, the tabs 43 prevent rotation of the supporting members 25 and 26 and the tabs 39 likewise prevent rotation of the supporting member 27 whereby said supporting members are held in 25 erected position so that the garments may be hung upon the same. After the supporting members are properly positioned the garment hanger is used in the customary manner.

Although I have illustrated the supporting 30 members of the invention as constructed from two strips of paper, glued together along the margins thereof, it can readily be comprehended that the same may be secured together by wire, stitching, riveting or otherwise. Also the said 35 supporting members may be constructed from single strips of paper and the stitching extended across the supporting member and frame member and forming a hinge therefor. In Fig. 5, which is a view similar to Fig. 3 of a modification of the 40 invention, this form of construction has been shown. In this figure the frame member has been designated by the reference numeral 117 and the supporting member by the reference numeral 127. In this case a single strip of material 45 is used and a number of staples 128 secured to the central portion 133 of the supporting member to pivotally attach the same to the frame member.

The advantages of my invention are manifest. 50 An extremely simple and practical construction is provided by means of which a garment hanger having the advantages of both a wire and a paper garment hanger is procured. The supporting means may be attached to any of the existing wire 55 garment hangers now in common use without alteration or reconstruction thereof. The supporting means being permanently mounted on the wire frame cannot become loose nor accidentally removed therefrom, as is frequently the 60 case where detachable supporting members are used. By means of the notches and tabs formed on the ends of the supporting members, the same are held in proper position with respect to the frame, thereby facilitating the use of the garment 65 hanger. My improved garment hanger can be constructed at a nominal expense.

Changes in the specific form of my invention, as herein disclosed, may be made within the scope of what is claimed without departing from 70 the spirit of my invention.

Having described my invention, what I claim as new and desire to protect by Letters Patent is:

1. A garment hanger comprising a wire frame having a plurality of frame members arranged in 75

co-planar relation, a supporting member consisting of two layers of paper normally substantially planiform and elongated in form, said layers being arranged on opposite sides of one of said frame members, said layers being secured together outwardly of said frame member to pivotally support the supporting member on said frame member.

2. A garment hanger comprising a wire frame having a plurality of frame members arranged in co-planar relation, a supporting member consisting of two elongated strips of paper applied to one of said frame members, said strips being disposed one on each side thereof and said frame member extending medially of the strips, said strips being secured together marginally to provide an elongated space intermediate the edges of the strips in which the frame member is disposed, said space accommodating swinging movement of the supporting member with reference to the axis of the frame member.

3. A garment hanger comprising a wire frame having a plurality of frame members arranged in co-planar relation, a plurality of elongated supporting members constructed of strips of paper normally planiform in shape and extending along said frame members, and other strips of paper normally substantially planiform and extending along the first named strips on the opposite sides of said frame members, said strips being secured together along both the lateral marginal portions thereof in contact with one another to envelope said frame members and to form longitudinally extending grooves serving as hinges for pivotally supporting said supporting members for swinging movement on said frame members, said supporting members being adapted to swing from substantially co-planar positions to positions extending substantially at right angles to the plane of the frame.

REYNOLDS GUYER. 20
